JOHN GARSED AND CLAYTON DENN, OF FRANKFORD, PENNSYLVANIA, ASSIGNORS TO JOHN GARSED.

Letters Patent No. 83,951, dated November 10, 1868.

IMPROVED MACHINE FOR PACKING TEA, COFFEE, &c.

The Schedule referred to in these Letters Patent and making part of the same.

To all whom it may concern:

Be it known that we, JOHN GARSED and CLAYTON DENN, of Frankford, in the county of Philadelphia, and State of Pennsylvania, have invented a new and improved Machine for Packing Tea, Coffee, &c.; and we do hereby declare that the following is a full, clear, and exact description thereof, which will enable those skilled in the art to make and use the same, reference being had to the accompanying drawings, forming part of this specification.

This invention relates to a new and improved machine for packing tea, coffee, &c., in paper bags, with a given weight of the article in each bag.

The object of the invention is to obtain a means, for the purpose specified, which will admit of the work being performed rapidly, and in a perfect manner, and without the employment of skilled labor.

In the accompanying sheet of drawings—

Figure 1 is a side sectional view of our invention, taken in the line *x x*, fig. 2.

Figure 2, a rear elevation of a portion of the same.

Similar letters of reference indicate corresponding parts.

A represents the framing of the machine, which may be composed of two uprights, *a a*, connected, at their upper ends, by a top plate, *b*, and by a cross-plate, *c*, some distance below the top plate *b*.

B represents a rectangular box, which passes through the top plate *b*, and is allowed to slide freely up and down the lower end of said box, being connected, by a rod, *C*, with a treadle, *D*, against the under side of which a spring, *E*, bears, said spring having a tendency to keep the treadle elevated.

This box *B* has no bottom directly attached to it, the upper end of the rod *C* being secured to the lower end of the box *B* by a rod, *d*.

What serves as a bottom for the box is a horizontal plate, *F*, supported by four uprights, *e*, secured to the cross-plate *c*.

This plate *F* is fixed, while the box, as before stated, is allowed to slide up and down, said motion being given it through the media of the treadle *D* and spring *E*.

G is a treadle, which is placed by the side of the treadle *D*, and has a spring, *H*, bearing against its under side.

I is an upright shaft, which is fitted loosely in a vertical tube, *J*, and is allowed to rise and fall, and turn freely therein.

The lower end of the shaft *I* is fitted on a rod, *K*, in such a manner as to form a secure connection, and at the same time allow the shaft *I* to turn freely upon it, the lower end of the rod *K* being attached to the treadle *G*.

The shaft *I* has a pin, *f*, projecting horizontally from it, having a roller fitted on it, which works in a slot in the lower part of tube *J*, the lower portion *G* of said slot being vertical, and the upper part *h* being spiral

or oblique. (See fig. 2.) This slot and pin cause the shaft *I* to turn in the tube *J* about a quarter of a revolution at the termination of its upward and at the commencement of its downward stroke.

To the upper end of shaft *I* there is secured a horizontal arm, *L*, which has a vertical shaft, *M*, at its outer end, the shaft *M* having a square or rectangular plunger, *N*, secured to its lower end.

This plunger *N* is hollow, and has within it a plate, *i*, to which a series of pendent rods, *j*, is attached, the latter, when pressed down, passing through the bottom of the plunger, and, when drawn up, being within the plunger, the latter position being shown clearly in fig. 2.

These rods are raised and lowered by having a rod, *k*, attached to it, which rod is fitted in the shaft *M*, and allowed to rise and fall freely therein.

This rod *k* has a pin, *l*, projecting horizontally from it, and this pin passes through a vertical slot, *m*, in shaft *M*, and also through a curved slot, *n*, in a collar, *O*, which is fitted loosely on the shaft *M*. This will be fully understood by referring to fig. 2.

P is a rectangular sheet-metal box, which is fitted in the box *B*.

This box *P* has a flaring upper end, *o*.

Q is a horizontal fork, which is attached to the upper end of a rising-and-falling bar, *R*, which is operated by a lever, *S*. This fork *Q* embraces the box *B*, a prong being at two opposite sides of it.

The operation is as follows: The tea, coffee, or other substance to be packed is weighed out in suitable quantities, and put into the box *P* as weighed, one quantity at a time. Previous to the placing of the box *P* in *B*,

paper is adjusted around its exterior, to form the bag, the lower edge of the paper being folded over the lower edge of *P*, to form the bottom of the bag. The box *P* is then placed in box *B*, the weighed substance put into *P*, and the treadle *G* forced down by the foot, the treadle *G*, as it descends, causing the plunger *N* to turn directly over the box *P*, and, when the plunger arrives at this position, it descends and packs the substance in the box. The lever *S* is then raised, and the fork *Q* forces upward the box *P*, free from the paper bag and its contents, which are retained in box *B*, the plunger *N*, which is still held down, preventing them from rising. The plunger *N* is then allowed to rise and swing around, and box *P* removed. The plunger is then again brought down on to the substance being packed, then allowed to rise and swing out of the way, the paper folded over and sealed, which completes the package. The box *B* is then forced down by the treadle *D* and connecting-rod *C*, leaving the package standing on the fixed bottom *F*, ready to be removed after having its top folded over.

By this arrangement, tea, coffee, and other substances may be packed in paper bags with great rapidity, and in a perfect manner.

The pendent-rods *j* are forced down out of the

plunger N in packing ground coffee and other finely-ground substances, which would be liable to cake under the pressure of the plunger. The rods j effectually prevent this result.

We claim as new, and desire to secure by Letters Patent—

1. The plunger N, attached to or connected with a rising-and-falling shaft, I, placed within a tube, J, connected with a treadle, G, and arranged substantially as shown, so that the plunger will have a rising-and-falling and also a turning movement communicated to it, for the purpose herein set forth.

2. The rising-and-falling box B, with the fixed bottom plate F, in combination with the plunger N, all arranged to operate substantially as and for the purpose specified.

3. The box P, in combination with the fork Q, rising-and-falling box B, and plunger N, all arranged substantially in the manner as and for the purpose set forth.

JOHN Garsed.
CLAYTON DENN.
